HUMIDIFIER AND SMOKE-CONSUMER SYSTEM

Application filed March 25, 1929. Serial No. 349,809.

This invention relates to devices for use in connection with heating systems for generating steam to increase the water vapour content of the air of an apartment and for using surplus steam generated to improve combustion in the furnace of the heating system, and my object is to devise simple and easily controllable means for this purpose which may be easily installed in connection with ordinary heating apparatus.

I attain my object by means of constructions which may be briefly described as follows. A vaporizer is located in the combustion chamber of the furnace of the heating system. Water is fed in a steady flow to the vaporizer and the generated steam is led to a suitable place of discharge. The pipe through which the steam is led off is provided with a controlling valve and a steam jet is provided on the vaporizer through which surplus steam is discharged into the combustion chamber of the furnace to aid combustion, or elsewhere if desired. The water supply means is preferably formed as a unitary casting including a drip, a trap into which the drip discharges and with which the vaporizer is connected, and an overflow discharging to a waste pipe.

The device is hereinafter more specifically described and is illustrated in the accompanying drawings in which

Fig. 1 is a front elevation of a furnace having my device installed therewith;

Fig. 2 is a cross section on the line 2-2 in Fig. 1;

Fig. 3 a side elevation of the vaporizer and its connections;

Fig. 4 a similar view of a modification; and

Fig. 5 a side elevation, partly in section, of the water supply and overflow portion of the device.

In the drawings, 1 is a furnace which may be of any ordinary construction and is provided with the fuel door 2 leading into the combustion chamber over the fire pot. In the combustion chamber is located a vaporizer 3, preferably of the tubular form shown. With this vaporizer are connected the water supply pipe 4 and steam pipe 5, preferably

by means of the special connection shown in Fig. 3, which is formed as a unitary casting having a connection 6 for the attachment of the vaporizer and two branches 7 and 8, one in approximate alinement with the vaporizer and the other extending above the former, these branches being formed with right angled pipe connections 9 and 10 connected respectively with the water supply pipe 4 and steam pipe 5, which extend through the side of the frame of the fuel door opening.

In the modification shown in Fig. 4, the water pipe is connected with the forward end of the vaporizer by the connections 11, while the steam pipe 5 is connected by means of suitable piping 12 with the inner end of the vaporizer. The construction of Fig. 3 is, however, preferred.

The water pipe 4 is supplied with water by water supply means 13, preferably formed as a unitary casting. This casting is shaped to form an open chamber 14, a connection 15 for the water pipe 4, a trap 16 between the two, a waste pipe 17, and an overflow 18 preferably extending from the side of the chamber 14 over the upper end of the waste pipe 17. The waste pipe 17 is connected with a pipe 19 which may be led to any convenient position for discharge.

The various parts described are so proportioned and positioned that when water is dripping from the overflow 18 the water level is partway only up above the lower side of the water pipe 4, leaving a steam space in the pipe and also in the upper part of the vaporizer. The connection between the water supply pipe 4 and the vaporizer is, however, located above the axis of the vaporizer so that there will usually be a greater depth of water in the vaporizer than in the water pipe. When water is supplied to the chamber 14 to maintain this water level, which is of course governed by the position of the overflow, steam will be generated in the vaporizer chamber and discharged through the steam pipe 5. This steam pipe is connected by a coupling 20 with the pipe 21 which is led to a discharge outlet 22 located in the floor of an apartment above the furnace or to any other position desired. In this pipe is located

a valve 23 whereby the amount of steam discharged from the outlet 22 may be controlled.

To ensure that an adequate supply of steam will be delivered at all times even when a low fire only is maintained in the furnace, I prefer to give the vaporizer sufficient heating surface to generate steam in excess of the requirements when a strong fire is maintained. This excess steam must be given some means of escape and I therefore provide in a convenient position an outlet for this excess steam, which excess steam is preferably led into the interior of the furnace to assist in smoke prevention. Preferably I provide a small outlet 24 in the casting 6, preferably valve controlled, whereby the outlet may be more or less restricted as may be necessary to compensate for the resistance to the flow of steam to the outlet 22 which depends to a considerable extent on the distance of the outlet from the furnace. By controlling the outlet 24, an adequate supply is assured to the outlet 22, while by using the valve 23 the amount of steam passing from the outlet 22 may be regulated, any excess passing away through the outlet 24. Preferably the water supply pipe 4 and the steam pipe 5 are connected by the pipe 25 so that any steam passing back through the water pipe may pass up to the steam pipe 5 and thence to the pipe 21, and any drip back through the pipe 21 is led directly to the water supply pipe.

The water supply means is fed by the water pipe 26, which will usually be connected with a water supply service. Formed integral with the wall of the chamber 14 is a connection 27 for the pipe 26. This connection has a side outlet with which is connected the drip valve 28 which discharges into the chamber 14. By means of this valve a suitable quantity of water is regularly supplied to the chamber so that when the device is in operation a drip is maintained from the overflow 18, thus ensuring the maintenance of a constant water level in the system. The bottom of the drip 16 is preferably provided with a sediment chamber closed by the plug 29.

In the form of vaporizing chamber shown in Fig. 4, the valve controlled outlet 24 is shown at the connection between the steam pipe 5 and the piping 12.

As dust or dirt may pass down through the outlet 22 and accumulate in the pipe 21 below the outlet as a sediment, I form a sediment trap 30 in the pipe 21 below the outlet which may be opened and cleaned from time to time.

From the above description it will be seen that I have devised a humidifying device which will satisfactorily attain the objects of my invention as set out in the general statement of the invention.

What I claim is:

1. A humidifier system comprising a vaporizer adapted to be located in the combus-

tion chamber of a furnace; means for supplying water thereto; a steam pipe leading therefrom to discharge into the atmosphere at a point above the vaporizer; a steam jet connected with the vaporizer adapted to discharge into the furnace; and means for regulating the relative proportion of steam passing through the outlets thus provided. 70

2. A humidifier system comprising a vaporizer adapted to be located in the combustion chamber of a furnace; means for supplying water thereto; a steam pipe leading therefrom to discharge into the atmosphere at a point above the vaporizer; a steam jet connected with the vaporizer adapted to discharge into the furnace; and means for regulating the relative proportion of steam passing through the outlets thus provided, comprising a valve in the steam jet pipe. 75

3. A humidifier system comprising a vaporizer adapted to be located in the combustion chamber of a furnace; means for supplying water thereto; a steam pipe leading therefrom to discharge into the atmosphere at a point above the vaporizer; a steam jet connected with the vaporizer adapted to discharge into the furnace; and means for regulating the relative proportion of steam passing through the outlets thus provided, comprising a valve in the discharge pipe and a valve in the steam jet. 85 90

4. A humidifier system comprising a vaporizer; a steam pipe leading therefrom; a water pipe leading thereto; and water supply means therefor comprising a unitary casting forming an open chamber, a connection for the water pipe, a trap between the two, a waste pipe, and an overflow discharging to the waste pipe. 100

5. A humidifier system comprising a vaporizer; a steam pipe leading therefrom; a water pipe leading thereto; water supply means therefor comprising a unitary casting forming an open chamber, a connection for the water pipe, a trap between the two, a waste pipe, and an overflow discharging to the waste pipe; and a connection on the wall of the chamber for a water pipe having a side outlet over the mouth of the chamber. 105

6. In a humidifier system the combination of a vaporizer chamber; and a water and steam connection therefor comprising a unitary casting having a connection for the attachment of the vaporizer chamber, and two branches, one in approximate alinement with the vaporizer chamber and the other extending above the former, each being formed with a pipe connection; a water supply pipe secured to one connection; and a steam outlet pipe secured to the other. 115 120

7. In a humidifier system the combination of a vaporizer chamber; and a water and steam connection therefor comprising a unitary casting having a connection for the attachment of the vaporizer chamber, and two 130

branches, one in approximate alinement with the vaporizer chamber and the other extending above the former, each being formed with a pipe connection, the connections extending laterally in the same direction and parallel to one another; a water supply pipe secured to one connection; and a steam outlet pipe secured to the other.

8. In a humidifier system the combination of a vaporizer chamber; and a water and steam connection therefor comprising a unitary casting provided with a steam jet opening at one side and having a connection for the attachment of the vaporizer chamber, and two branches, one in approximate alinement with the vaporizer chamber and the other extending above the former, each being formed with a pipe connection; a water supply pipe secured to one connection; and a steam outlet pipe secured to the other.

9. A humidifier system comprising a vaporizer adapted to be located in the combustion chamber of a furnace; means for supplying water thereto; a steam pipe leading therefrom to discharge into the atmosphere; a restricted discharge for steam adjacent the vaporizer; and means for regulating the relative proportion of steam passing from the outlets provided.

10. A humidifier system comprising a vaporizer adapted to be located in the combustion chamber of a furnace; means for maintaining a constant water level in the vaporizer; a steam pipe leading from the vaporizer at a point above the water level therein and discharging to the atmosphere in an adjacent apartment at a level above the vaporizer; a separate discharge for surplus steam leading from the vaporizer above the water level therein to a point other than in said apartment; and means for regulating the relative proportion of steam passing from the outlets provided, whereby dry steam may be supplied for moistening the air of the apartment in a predetermined volume and excess steam led elsewhere.

11. A humidifier system comprising a vaporizer adapted to be located in the combustion chamber of a furnace; means for maintaining a constant water level in the vaporizer; a steam pipe leading from the vaporizer at a point above the water level therein and discharging to the atmosphere in an adjacent apartment at a level above the vaporizer; a separate discharge for surplus steam leading from the vaporizer above the water level therein to mingle with the products of combustion of the furnace; and means for regulating the relative proportion of steam passing from the outlets provided, whereby dry steam may be supplied for moistening the air of the apartment in a predetermined volume and excess steam led elsewhere.

12. A humidifier system comprising a vaporizer; a steam pipe leading therefrom; a

water pipe leading thereto; and water supply means therefor comprising a unitary casting forming an open chamber, a connection for the water pipe, a trap between the two, a waste pipe, and an overflow discharging to the waste pipe, said waste pipe being located between the legs of the trap.

Signed at Toronto, Canada, this 6th day of March, 1929.
